Primary Examiner—Catherine Tuttle(74) *Attorney, Agent, or Firm*—Sterne, Kessler, Goldstein & Fox P.L.C.(57) **CLAIM**

The ornamental design for a bottle, as shown and described.

DESCRIPTION

FIG. 1 is a front perspective view of a first embodiment of a bottle showing my new design;

FIG. 2 is a side view thereof, the opposite side view being a mirror image thereof;

FIG. 3 is a rear view thereof;

FIG. 4 is a front view thereof;

FIG. 5 is a top plan view thereof;

FIG. 6 is a front perspective view of a second embodiment of a bottle showing my new design;

FIG. 7 is a side view thereof, the opposite side view being a mirror image thereof;

FIG. 8 is a rear view thereof;

FIG. 9 is a front view thereof; and,

FIG. 10 is a top plan view thereof.

The broken lines in the Figures are included for the purpose of illustrating associated environmental structure which forms no part of the claimed design.
